UNITED STATES PATENT OFFICE

110,135

DESIGN FOR A DRESS

Henry Schultz, Brooklyn, N. Y.

Application May 12, 1938, Serial No. 77,136

Term of patent 3½ years

To all whom it may concern:

Be it known that I, Henry Schultz, a citizen of the United States of America, residing in the city of Brooklyn, New York, have invented a new, original, and ornamental Design for a Dress, of which the following is a specification, reference being had to the accompanying drawing, forming part thereof, wherein,

Fig. 1 is a front view of a dress and Fig. 2 is a rear view of a dress.

I claim:

The ornamental design for a dress, substantially as shown.

HENRY SCHULTZ.
